CLAIM

The ornamental design for a recessed ceiling light, as shown and described.

DESCRIPTION

FIG. 1 is a bottom perspective view of a recessed ceiling light showing our new design;

FIG. 2 is a top perspective view thereof;

FIG. 3 is a bottom view thereof;

FIG. 4 is a bottom view thereof, showing the design with transparent sections, illustrated by cross-hatching;

FIG. 5 is a front view thereof; the back view being identical thereto;

FIG. 6 is a right side view thereof; the left side view being identical thereto;

FIG. 7 is a top plan view thereof;

FIG. 8 is a sectional view taken along line 8-8 in FIG. 7;

FIG. 9 is a sectional view taken along line 9-9 in FIG. 3; and,

FIG. 10 is a partial enlarged view showing section 10-10 of FIG. 9.

The oblique solid-line and broken-line pattern shown in FIGS. 4, 9 and 10 indicates that the surface is transparent. The broken line portions in the drawings are included to illustrate environmental structure and form no part of the claimed design.
